UNITED STATES PATENT OFFICE

2,424,411

PRODUCTION OF NARROW CURVILINEAR
NONELASTIC TAPE

John V. Moore, Pawtucket, R. I., assignor to
Moore Fabric Company, Pawtucket, R. I., a
corporation of Rhode Island

Application May 27, 1946, Serial No. 672,635

1 Claim. (Cl. 139—384)

1

This invention relates to the production of narrow curvilinear non-elastic tape, such as zipper tape. A curvilinear zipper tape, with the bead at the short or concave edge, has substantial advantages in use, as coacting curved zipper tapes are more quickly and easily connected and, when connected, they fit more smoothly over contoured surfaces.

It is the general object of my invention to provide a curvilinear non-elastic zipper tape or the like with an improved weave construction by which the tape has a controlled and regular longitudinal curvature, and with the cord, if for zipper use, located at the short or concave edge of the tape.

A further object is to provide an improved method of production of a narrow curvilinear non-elastic tape with controlled curvature.

One form of mechanism adapted for the carrying out of my invention is shown in the drawings, in which

Fig. 1 is a perspective view of parts of a narrow ware loom on which narrow curvilinear non-elastic tape may be woven by my improved method;

Fig. 2 is a diagrammatic view illustrating the beaming of a warp for use in making my improved tape;

Fig. 3 is a plan view of a portion of my improved tape; and

Fig. 4 is a transverse section of the tape.

Referring to Fig. 1, which is more or less diagrammatic, I have shown such parts of a narrow-ware loom as are necessary to disclose and explain my invention.

I have shown a breast beam 10, a lay 11 provided with guide-blocks 12 for a narrow-ware shuttle (not shown), and a reed 13 which is preferably graduated and has its dents placed more closely together toward the right-hand end of the reed as viewed in the drawing. I have also shown a plurality of harnesses 15 and a warp guide-roll 17 positioned substantially at the rear of the harnesses.

Non-elastic warp threads W are supplied from a tapered warp beam 20, rotatably mounted and provided with a suitable friction device 22. A non-elastic cord C is supplied from a separate cylindrical warp beam 30, also rotatably mounted and provided with a friction device 32. Non-elastic warp threads W' for weaving the tube or sleeve S (Fig. 4) are supplied from a third and cylindrical warp beam 40 which is rotatably mounted and has a separate friction device 41. The warp threads W and W' and the cord C pass from the warp beams 20, 30 and 40 over a guide-

2

bar 34 and through an assembly reed 35 to the guide-roll 17. The reed 35 is preferably graduated to correspond to the reed 13 on the lay 11.

The tape T passes over a guide-roll 45 on the breast beam 10, which guide-roll should also be tapered as indicated in the drawing. The tape T then passes around a tapered take-up roll 50 and a cylindrical guide-roll 51 and is wound on a tapered cloth roll 52. The roll 50 is mounted on a take-up shaft 54 which is positively driven.

The usual mechanism is provided for raising and lowering the harnesses and for reciprocating the shuttle by which the non-elastic wefts F (Fig. 3) are inserted.

15 In Fig. 2, I have indicated the preferred beaming of the warps W on the tapered warp beam 20 by drawing the warps through a graduated reed 60, with the dents more closely spaced toward the larger end of the beam 20.

20 Production of my improved narrow curvilinear non-elastic tape T by the mechanism described is accomplished as follows:

The warp threads W are first beamed on the tapered warp beam 20 by drawing the warps 25 through the graduated reed 60 as shown in Fig. 2, which results in the warps W being longer and more closely spaced at the larger end of the beam 20, and in being gradually shortened and more widely spaced toward the smaller end of the beam.

25 The tape T is then woven by drawing the warps W and W' and the cord C through the graduated reed 35 to the harnesses 15 and thence through the graduated reed 13 on the lay 11, at which point the non-elastic wefts F are inserted by the usual positively-driven shuttle which is reciprocated between the guide-blocks 12. The tape T is then drawn downward over the tapered guide-roll 14 by the positively rotated and tapered take-up roll 50, and is wound on the tapered cloth roll 52.

30 The supplying of non-elastic warp threads W of greater length and more closely spaced at the right-hand edge of the tape T (as viewed in Fig. 1) provides a controlled curvature for the tape, 35 which is woven longer and substantially convex at its right-hand edge. This curvature is preserved by drawing down the tape by the tapered take-up roll 50 and by winding the tape on the tapered cloth roll 52.

35 The threads at the right-hand edge of the warp are longer and are drawn more rapidly through the reed 13 than those at the left-hand or shorter edge, the weft threads are fanned-out and are slightly more widely spaced at the convex edge of the tape.

40 As the threads at the right-hand edge of the warp are longer and are drawn more rapidly through the reed 13 than those at the left-hand or shorter edge, the weft threads are fanned-out and are slightly more widely spaced at the convex edge of the tape.

3

By combining the graduated spacing of the non-elastic warps on the tapered warp beam 20 with the provision of the tapered reed 13 at the weaving point and by winding down the tape more rapidly at the longer and more closely woven edge, a definite and accurately controlled curvature may be imparted to the non-elastic tape T.

If the tape is intended for zipper purposes, the relatively heavy cord C is inserted in a sleeve S 10 at the shorter or concave edge of the tape.

Having thus described my invention and the advantages thereof, I do not wish to be limited to the details herein disclosed, otherwise than as set forth in the claim, but what I claim is:

The method of weaving narrow curvilinear non-elastic zipper tape which consists in supplying non-elastic regular warp threads faster and with closer spacing at the convex edge of the tape to be woven, supplying a relatively shorter and thick non-elastic cord warp adjacent the concave edge of the tape and from a separate source of supply, supplying special non-elastic warp

5

4

threads from a third source of supply to form a tube for said cord warp, taking up the woven tape faster along the convex edge, and inserting wefts which are increasingly spaced apart toward the convex edge of the tape by the more rapid feed and more rapid take-up of the regular warp threads at said convex edge.
